United States Patent

Des. 240,763
Patented July 27, 1976

240,763

CUTTING TOOL

Richard W. Clemens, Jr., 9201 Wellington Court,
Seabrook, Md. 20801

Filed Oct. 4, 1974, Ser. No. 512,054

Term of patent 14 years

Int. Cl. D8—03

U.S. Cl. D54—4

FIG. 1 is a side elevation view of a cutting tool;
FIG. 2 is a fragmentary front elevation view of the
cutting tool viewing from the right side of FIG. 1;

FIG. 3 is a fragmentary rear elevation view of the
cutting tool viewing from the left side of FIG. 1; and

FIG. 4 is a top plan view of the cutting tool.

I claim:

The ornamental design for a cutting tool, as shown and
described.
